B. F. GARDNER.
AUDIBLE SOUND INSTRUMENT.
FILED AUG. 4, 1921.

UNITED STATES PATENT OFFICE.

BENJAMIN FULTON GARDNER, OF CHICAGO, ILLINOIS.

AUDIBLE SOUND INSTRUMENT.

Application filed August 4, 1921. Serial No. 489,897.

To whom it may concern:

Be it known that I, BENJAMIN FULTON GARDNER, a citizen of the United States, residing at Chicago, in the county of Cook 5 and State of Illinois, have invented a certain new and useful Improvement in Audible Sound Instruments, of which the following is a full, clear, concise, and exact description, reference being had to the accompanying drawings forming a part of this specification.

Primarily the object of my invention is to easily and quickly determine the quantity of oil in a tank that contains both oil and water. As the water line beneath the oil is not visible various means are used to enable a gager to obtain the data necessary for his report. The large wooden tanks in oil fields are kept as nearly full of fluid as 15 possible, in order to protect them, otherwise they would dry out—causing leakage at the stave joints. The water content is frequently greater than that of the oil. Oil pumped from the well holds water in suspension. 20 Again, oil and water in varying proportions reach the tank from the well. It is necessary to draw the water off or remove samples of the fluid at various points in order to estimate the content of oil upon the water. 25 Unless oil in "tank is ready to be run into the pipe lines" it is not customary to discharge the water; and as gagers with their sampling apparatus are not on the ground, the operator or pumper is unable to report 30 so many barrels of oil in tank, or "tank ready to be run". The more facile sounding of the water-line in tanks is the object of my invention.

To the above ends, the invention consists 40 in matters hereinafter described and more particularly pointed out in the appended claim.

The practical operation of my invention may be more readily understood by a description of the same, in conjunction with the use of one practical form of apparatus whereby it may be carried out.

I have illustrated my invention by reference to the accompanying drawings in 50 which—

Figure 1, is a broken sectional view of a tank showing oil above and water below and my device in connection therewith.

Fig. 2, is a view in elevation of a reel with 55 the front half of its casing removed.

Fig. 3, is an enlarged sectional view taken

at the line 3, of Fig. 1, showing a telephone receiver mounted in the reel with conductors embedded in tape spooled thereon.

Figure 4, is a broken-face view of a portion of the tape showing the wires embedded therein.

Fig. 5, is a vertical, sectional view of the plummet showing sectional views of galvanic elements therein.

Fig. 6 is a top view of said plummet showing an insulating part upon which the galvanic elements are mounted, said part perforated so that fluid can freely circulate through said plummet and energize or de- 70 energize the galvanic elements therein.

The operation of my invention, which I term a "Telesound", is obviously simple. To illustrate: The pumper or field boss is required to report "oil in tank". He goes upon 75 the tank, connects the plummet to the line, unreels a few feet of the tape, places the receiver to this ear, lowers the plummet into the fluid and slowly allows it to descend. When passing through the oil, the 'phone or signal, if it is a buzzer or bell, is silent. When the water-line is reached and the plummet is but a fraction of an inch in the "brine", a loud click is heard, current is 80 generated and the telephone receiver is in action. At this point the operator notes the oil-mark on the scale. Assume the click is heard when the tape-scale indicates 3', 6". To check the gage he raises the plummet an inch—the 'phone is silent—it is out of 85 the salt water and into oil. Further, he is required to report the sediment as it is called by well workers. After noting the content of oil, the plummet is allowed to descend through the water strata; a continuous humming is heard. The 'phone is in violent action so long as the plummet is in contact with the salt water. The humming noise ceases, or the density of the sound is lowered. The tape now shows 6', 1", the 90

plummet has reached the sediment and the soapy emulsion interferes with the galvanic action of the elements. The plummet is lowered through this jelly-like sediment to the tank bottom and the tape shows 6', 10". In this case the operator's report would show: Tank No. 1.—2 $\frac{1}{2}$ barrels per inch. Oil; three feet, six inches; water; two feet, eleven inches; sediment; nine inches. Referring to the official tank-chart, the quantity of the various fluids is read off and stated in barrels and fractions of a barrel.

or gallons. The linear measure is translated by the tank-chart into the liquid measure used in the oil trade.

Having described my invention, what I claim as new, and desire to have covered by Letters Patent is:—

An audible sound instrument comprising a tape-line with suitable measuring scale, a case, a telephone receiver pivotally mounted in said case, said tape-line spooled upon said telephone receiver and means to rotate said

telephone receiver, a plummet compounded of galvanic elements, a circuit carried by said tape-line from said telephone receiver to said plummet to energize the former from 15 the latter.

In witness whereof, I hereunto subscribe my name this 26th day of July A. D., 1921.

BENJAMIN FULTON GARDNER.

Witnesses:

AMELIA WUNDSAM,
A. W. D. BRADFIELD.
